MOBILE SCOOP FOR LIFT TRUCKS

Lloyd Thurman Graves, North Vancouver, British Columbia, Canada, assignor, by direct and mesne assignments, of sixty-six and two-thirds per cent to William Blaylock Steele, Vancouver, British Columbia, Canada

Application October 24, 1947, Serial No. 781,945

20 Claims. (Cl. 214—120)

1

This invention relates to improvements in scoops, and particularly that character of scoop mounted for elevational movement and also for swinging movement about a transverse horizontal axis, and which is carried upon a tractor or other suitable vehicle to give the same mobility for the effective handling and moving of dirt, rock, and other like materials. The procedure, in using a scoop of the character to which the present invention pertains, is to first position the scoop-bucket at a ground level and with the digging blade located horizontally. By the driving energy of the vehicle, the open maw of the scoop-bucket is then driven into a bed of the material being handled, moving forwardly in such degree as is necessary to pick up the desired load, following which the bucket is first tilted upwardly to preclude spilling and is then elevated to a carrying height, the bucket being locked against a reverse swing while the vehicle moves to the desired point of discharge where the load is dumped by a disengagement of the lock to allow the bucket to swing downwardly by the weight of the load.

As a particular object, the invention aims to provide a highly efficient bucket-elevating mechanism including a vertically movable carriage and having recourse to a lift-chain as the medium for transferring to the carriage the energy derived from a hydraulic ram or other source of power.

It is a further and important object to apply this chain such that, in addition to the performance of the carriage-elevating office, the chain transmits to the bucket the energy necessary to accomplish the motion of tilting the same from loading to carrying position.

As a further corollary object, the invention aims to devise a scoop in which the chain, by force of energy derived from the activating motor, operates to sequentially accomplish the steps, first, of tilting the bucket and then raising the same.

Other objects and advantages of the invention, concerned more especially with the provision of a particularly simplified, easily operated, and trouble-free mobile scoop will, with the foregoing, appear and be understood in the course of the following description and claims, the invention consisting in the novel construction and in the adaptation and combination of parts hereinafter described and claimed.

In the accompanying drawings:

Figure 1 is a fragmentary side elevational view with parts in section to illustrate a mobile scoop constructed in accordance with the preferred embodiment of the present invention, the scoop-

2

bucket being shown by full lines in its lowered loading position and being also shown by dotted lines in an elevated dumping position.

Fig. 2 is a fragmentary view partly in elevation and partly in section to detail the head end of the telescoping frame and permit a full-line showing of the chain-receiving roller and its frame mounting.

Fig. 3 is a horizontal sectional view taken to an enlarged scale on line 3—3 of Fig. 1.

Figs. 4 and 5 are fragmentary longitudinal vertical sectional views on lines 4—4 and 5—5, respectively, of Fig. 3.

Figs. 6 and 7 are views similar to Fig. 4 and 15 Fig. 5, respectively, excepting that the parts are here shown in the positions which they occupy when the bucket has been tilted upwardly into load-carrying position.

Fig. 8 is a view which, likewise, is similar to 20 Fig. 4 excepting that the upward tilt of the bucket has been here carried to a yet further degree, in which position the bucket is freed from the lift-chain and swings downwardly as indicated by the direction arrow to dump the load.

Fig. 9 is a view showing the various operating 25 parts in much the same positions as in Fig. 8 but with the released bucket having swung into dumping position.

Fig. 10 is a detail fragmentary transverse vertical sectional view taken to an enlarged scale 30 on line 10—10 of Fig. 8.

Fig. 11 is a fragmentary view partly in side elevation and partly in section to detail the toggle-jointed arms which are made subject to a spring 35 load in opposition to the lift force of the hydraulic ram and which function, after a dumping operation and when relieved of the restraint of the ram's hydraulic energy, to return the tail extremity of the lift-chain into the extended position in 40 which it is shown in Fig. 4; and

Fig. 12 is a detail fragmentary horizontal sectional view taken to an enlarged scale on line 45 12—12 of Fig. 6.

With reference being had to said drawings, 50 the vehicle which forms a mobile mounting for the scoop is indicated as being of that character providing two traction wheels 20 at the front and having a single steerable wheel (not shown) at the rear. An operator's seat is shown at 21, but other than for a steering wheel 22 and a trip-cord serving a purpose hereinafter to be described, the controls which govern the operation of the vehicle and the operation of the scoop-bucket, and which are or may be conventional, 55 are deleted from the drawing in order to simplify

the illustration. The vehicle desirably presents a horizontal platform 23 extending forwardly from the operator's station, and footing upon and made rigid with this platform is an upright cylinder 24 having hydraulic connection with a fluid pump driven from the engine of the vehicle. A piston (not shown) is slidably received within the cylinder, and fast to this piston is a piston-rod projecting above the upper end of the cylinder and presenting a furcate extremity 26 accommodating the journal mounting of a sheave 27. The lift cylinder might perforce be of the displacement rather than the piston type. Forward of the hydraulic cylinder and supported by the frame of the vehicle the invention provides a pair of posts placed in spaced paralleling relation and each being of a telescoping nature comprised of a stationary channel member slidably connected therewith. As shown, the outer channel 28 of each telescopically associated set of two is the stationary member and the inner channel 29 is the movable member, and these channels have their gutters correspondingly directed with the slide connection being comprised of vertically-spaced rollers, as 30, carried by the back wall of one said channel member and received in the gutter of the other member to track upon the side walls of the latter. For securing the one to the other of said inner and movable channel members to form a unit framework, the same are connected top and bottom by cross-ties, and there is also provided adjacent said bottom tie and extending across the back flanges of the channels an angle-iron 31. This movable framework has hung from its head end and journaled in a hanger 32 a sheave 33. In rigidifying the stationary framework composed of the outer channel members 28, the same are yoked by a brace 34 to the head end of the cylinder 24, and extending diagonally from the cylinder to the platform 23 is a stiffening strut 35.

The invention provides two complementary lift-chains, one of which, designated 36, is anchored by one end to a chair 37 secured upon the strut and, passing therefrom over the sheave 27, extends by its other end to the lower end of the movable framework whereat it is secured to the angle-iron 31. The other chain, denoted 38, is anchored by one of its ends to a cross-bar 40 fast to the stationary framework and from this anchor the chain passes over the sheave 33 and finds operative interconnection by its other end with the bucket.

Proceeding now to describe this operative interconnection, the bucket, which I denote 41, is provided at each side with a trunnion pin 42 journaled for swivel action in cheek-arms 39 extending forwardly from a U-shaped harness 43. Considered in side elevation, the back side of the bucket has a more or less semi-circular shape with the perimeter disposed concentric to the swivel axis of the bucket, and overlying a part of this concentric perimeter is the back wall 44 of the harness. The harness has transverse flanges 45 and 46 placed top and bottom of the back wall for stiffening the latter, and there is welded to the back wall and to the flanges to occupy a position central to the width a pair of spaced plates 47. Received between these plates and journaled upon pins carried by the latter are tandem-mounted rollers 48, and passing under these rollers and through a registering opening 50 of the harness' back wall 44 is the bucket-engaging end of the chain 38. Completing the harness proper and engaged by a pivot-

pin 51 to serve as hangers for suspending the harness from a vertically movable carriage 52 are upstanding arms 53, and these arms, as with the plates 47, are made an integral part of the harness by welding the same to the back wall and to the flanges.

The carriage, considered in front elevation, is of a generally rectangular configuration and is or may be fabricated from four upright plates disposed in spaced paralleling relation and weld-connected across the top and bottom by horizontal ties. The two inner plates, designated 58, are of somewhat greater width than the end plates and project rearwardly to overlie the inner faces of the channel members 29 and for the purpose of giving sliding support to the carriage these rear prolongations in each instance mount a pair of vertically spaced rollers 60 which work in the exposed gutters of the channels. As will be seen from an inspection of Figs. 4 through 9, inclusive, the several hanger-arms 53 and the plates 47 bear at their lower ends against the bottom cross-tie of the carriage to transmit to the latter the thrust force of the bucket. It is here pointed out that there is provided an angle-bar 61 made integral with the roller-carrying plates 58, and secured to this angle-bar is a normally inactive fitting 62 to which the end of the chain 38 is attached when the vehicle's load-handling equipment is comprised of a fork-lift rather than the illustrated scoop-bucket. The purpose of this fitting, in more particularity, is to enable the chain to be attached directly to the carriage and is used only when the bucket and its harness are replaced by the fork-lift attachment, the fork-lift being comprised simply of two L-shaped arms of which the upright elements of the L constitute hangers and are attached to the pivot-pin 51 and also bear upon the bottom cross-tie of the carriage in substantially the same manner as the hanger-arms 53.

Reverting to the bucket and its harness to describe the operating mechanism, a lug 63 is welded or otherwise fixedly secured upon the frontal face of the flange 45 to lie central to the width of the latter, and threaded through this lug is a set-screw 64 fitted with the usual jam-nut. Engaged by this set-screw is a block 65 mounted for vertical slide movement between stationary bars 66, and complementing the bars to guidably hold the block are headed bolts 67 working in slots cut in the underlying flange. The block is bifurcated at the bottom, and the setting is such that the feet 68 thereby described are brought very nearly into touching engagement with the perimeter of the bucket, and such, more especially, as will cause the feet to occupy an interruptive position in the path of swing movement of a pair of separated twin dogs 70, these dogs having a pivotal connection with the bucket and being normally urged by the action of a leaf or coil spring 71 into a position exposed beyond the bucket's perimeter. In accomplishing its bucket-rolling function, the chain 38 is caused to engage these dogs, being passed forwardly from the rollers 48 and the registering opening 50 through the interstice described between the feet 68, and presents upon its free end a pawl-block 72 which extends laterally beyond opposite sides of the chain and serves to catch against the frontal faces of the two dogs. This pawl-block is suspended by a flexible link 73 from the free end of an extensible jointed arm of which the outer section 74 is pivoted as at 75 to the inner section 76 and the latter in turn pivoted as at 77 to the harness. Working counter to take-

up pressure applied upon the chain from the hydraulic motor, the arm is normally extended by the action of a spring-pressed plunger 78 working against one section of the jointed arm and housed in a cylinder 79 which is trunnion-mounted from the other section of the arm.

Considered in a direction circumferential to the axis of the bucket, the placing of the dogs is such that a motor-activated take-up of the chain with a responsive rolling of the bucket will bring the dogs into tripped engagement with the feet 68 only when the bucket has been tilted upwardly into substantially the position in which it is shown in Fig. 8. However, there is provided upon the bucket in laterally off-set relation to the dogs a stop-lug 80 and immediately before this tripping action takes place such stop-lug is caused to be brought up against the pawl-finger 81 of a lever 82 which is given a trunnion mounting, as at 83, in pillow-blocks 84 bolted upon the frontal face of the harness. A spring 85 acts upon the lever to releasably hold the same against the stop, and for releasing purposes the trip-rope hereinbefore referred to, and designated 86, attaches to the outer end of the lever and extends therefrom to the driver's station of the vehicle. In addition to its contact with the stop-lug, the pawl-finger of the release lever is also caused, at a point in the rolling movement of the bucket, to lodge between double keepers 87 which are circumferentially removed from the stop-lug, the positioning of these keepers, more especially, being such that the pawl-finger finds engagement therewith when the bucket occupies the loading position in which it is shown in Figs. 1, 4 and 5.

Describing the operation of the scoop, and assuming that the bucket occupies an elevated position and has been dumped (see Fig. 9), the procedure is to lower the bucket until the digging blade touches the ground and at the same time move the vehicle slowly in a backward direction. The bucket will then roll itself as the digging blade levels off, and when so levelled the double keepers 87 will have been brought into registration with the pawl-finger to cause the latter to snap into a locking position between the same. The operator holds the control lever of the hydraulic motor depressed and this allows the spring load of the plunger 78 to move the jointed arm into its extended position whereupon the pawl-block 72 falls into position ahead of the two dogs 70. With the parts so located, the operator can, should he so desire, lift the bucket to elevate the digging blade in such degree as a given work may require inasmuch as the lock precludes the bucket from rolling and any take-up upon the chain simply elevates the bucket, its harness, and the carriage bodily. The nature of the hydraulic motor is such that the bucket will hold itself at any given height, a positioning of the motor's control lever at neutral producing a hydraulic lock.

In working into the pile of material being handled, the machine need usually be driven forward only until the digging blade makes contact with the pile, the momentum of the vehicle then filling the scoop. When the scoop has penetrated to its maximum depth, the trip-rope is pulled to withdraw the pawl-finger from the double keepers and the hydraulic motor is activated by a movement of its control lever to "raise" position, causing the chain to draw up. The bucket, being relieved of the pawl-finger's locking action, responsively rolls from its said loading position into the carrying position shown in Figs. 6 and 7, and which is to say until the stop-lug 80 brings up

against the pawl-finger, the trip-rope which controls lever 82 having been released after the roll has progressed through a few degrees of travel. After the stop-lug interrupts the rolling movement, the bucket then starts to raise, and the hydraulic control lever is kept in its "raise" position until the desired height is reached, whereupon the vehicle with its elevated load is moved to the dumping station, dumping being accomplished by simply pulling the release rope to disengage the pawl-finger from the stop-lug and momentarily placing the hydraulic control lever in "raise" position to cause the bucket to roll through an additional few degrees of travel into the position of Fig. 8, with consequent depression of the dogs 70 freeing the same from the pawl-block.

It may be here pointed out that the bucket, should it be so desired, can be dumped without transmitting thereto the tail-end roll necessary to bring the dogs into engagement with the tripping feet 68, and this is accomplished by pulling on the release rope while at the same time quickly activating the hydraulic control lever to allow the bucket to fall sharply through a few inches of travel, this procedure permitting the weight load to jar the pawl-block which, momentarily relieved of the draw force of the hydraulic motor, is kicked out of engagement with the dogs.

In stressing the machine's versatility, it should, perhaps, be here reiterated that the carriage of the present invention forms a basic unit on which several attachments can be installed, the two mentioned attachments, and namely the scoop-bucket and the fork-lift, being indicative. The machine is highly maneuverable, is extremely rugged in construction with unusually simple controls, and assures trouble-free operation even under the hardest usage.

The invention will, it is thought, have been clearly understood from the foregoing detailed description having particular reference to the illustrated now-preferred embodiment, but it is self-evident that changes in details of construction may be resorted to without departing from the spirit of the invention and I therefore intend that the hereto annexed claims be read with only such restrictions as are expressly introduced thereto.

50 What I claim is:

1. In combination with a scoop-bucket having a swivel mounting and guidably supported for bodily vertical movement of the scoop and its swivel mounting, a source of power, and a flexible link operatively interconnecting the power source with the bucket and acting to transmit to the latter energy responsible for both rolling the bucket about its swivel axis and to bodily elevate the same, the connection between the link and the bucket being a hooking connection.

2. In combination with a mobile vehicle, and a swivel-mounted scoop-bucket guidably supported by the vehicle for bodily vertical movement of the scoop and its swivel mounting, a source of power for giving traction to the vehicle and also for activating the bucket, and a flexible link operatively interconnecting said power source with the bucket and acting to transmit to the latter the energy responsible for both rolling the bucket about its swivel axis and to bodily elevate the same, the connection between the link and the bucket being a hooking connection.

3. In combination with a carriage guidably supported for vertical movement, and a swivel-

mounted scoop-bucket supported by said carriage, a source of power, manually released means for locking the bucket in a loading position, and powered means engageable with the scoop-bucket and operable when said lock is released and acting automatically in response to an energizing of the power source for sequentially transmitting to the bucket and to the carriage an energizing force operative first to roll the bucket from said loading position into a load-carrying position and then to elevate the rolled bucket.

4. In combination with a carriage guidably supported for vertical movement, and a swivel-mounted scoop-bucket supported by said carriage and providing a digging blade adapted when loading to occupy a level position and arranged by swivel movement of the bucket to be tilted upwardly or downwardly into either a load-carrying or a dumping position, respectively, a source of power, a draw-link activated from the power source and arranged to be releasably connected with the bucket for rolling the bucket into its said load-carrying position, and means acting automatically by a de-energizing of the power source and when the bucket occupies its loading position for bringing the draw-link into said connection with the bucket.

5. The structure of claim 4 in which the means last recited comprises an extensible arm composed of jointed sections.

6. In combination with a carriage guidably supported for vertical movement, and a swivel-mounted scoop-bucket supported by said carriage and providing a digging blade adapted when loading to occupy a level position and arranged by the bucket's swivel-movement to be tilted upwardly or downwardly into either a load-carrying or a load-dumping position, respectively, means for releasably locking the bucket in said loading position, a stop engaged by the bucket in its upward tilting movement, a motor, and a draw-line connection from the motor to the bucket operating when the bucket is released upon an energizing of the motor to first roll the bucket into its said load-carrying position and then, as the rolling movement is interrupted by the stop, bodily elevating the bucket and its carriage.

7. In combination with a carriage guidably supported for vertical movement, and a swivel-mounted scoop-bucket supported by said carriage and providing a digging blade adapted when loading to occupy a level position and arranged by the bucket's swivel-movement to be tilted upwardly or downwardly into either a load-carrying or a load-dumping position, respectively, a stop engaged by the bucket when the bucket is swung upwardly into load-carrying position, a roller having a localized mounting in relation to the carriage, a motor, and a draw-line operatively interconnected by one end with the motor and by its other end with the bucket and characterized in that its bucket-engaging end runs downwardly to the roller and thence under the latter and horizontally over the bucket, said draw-line, upon an energizing of the motor, acting first to roll the bucket and then, as the rolling movement is interrupted by the stop, bodily elevating the bucket and its carriage.

8. A mobile scoop comprising, in combination with a self-energized vehicle: a telescoping framework carried upon the vehicle to occupy a vertical position, a carriage guidably supported by the movable element of said telescoping framework for vertical movement in relation thereto, a swivel-mounted scoop-bucket sup-

ported by the carriage and providing a digging blade adapted when loading to occupy a level position and arranged by swivel movement of the bucket to be tilted upwardly or downwardly into either a load-carrying or a dumping position, respectively, a hydraulic motor upon the vehicle comprised of an upright cylinder and a piston working in the cylinder, a piston-rod fast to the piston and exposed by its upper end beyond the head end of the cylinder, a chain-handling sheave carried by said exposed end, a second chain-handling sheave carried upon the head end of the movable telescoping element, a looped chain anchored at one end to the vehicle with its bite passing over the first-named sheave and having its other end connected to the lower end of said movable telescoping element, and a second looped chain anchored at one end to the head end of the stationary telescoping element with its bite passing over the second-named sheave, the other end of the second said chain being adapted to be connected with the bucket for both rolling and elevating the latter.

9. A mobile scoop comprising, in combination with a self-energized vehicle: a telescoping upright framework carried upon the vehicle, a carriage guidably supported by the movable element of said framework for vertical movement in relation thereto, a swivel-mounted scoop-bucket supported by the carriage and providing a digging blade adapted when loading to occupy a level position and arranged by swivel movement of the bucket to be tilted upwardly or downwardly into either a load-carrying or a dumping position, respectively, a stop engaged by the bucket in its upward tilting movement, a hydraulic motor upon the vehicle comprised of an upright cylinder and a piston working in the cylinder, a piston-rod fast to the piston and exposed by its upper end beyond the head end of the cylinder, a sheave carried by said exposed end, a second sheave carried upon the head end of the movable telescoping element, a chain anchored at one end to the vehicle and passing over the first-named sheave with its other end connected to the lower end of said movable telescoping element, and a second chain anchored at one end to the head end of the stationary telescoping element and passing over the second-named sheave with its other end operatively interconnected with the bucket for first rolling the bucket from the latter's loading position into said load-carrying position and then, as the rolling movement is interrupted by the stop, bodily elevating the bucket and the carriage.

10. A mobile load-handling machine comprising, in combination with a self-energizing vehicle, a framework supported to occupy a vertical position upon the vehicle, a carriage guidably supported by the framework for vertical movement in relation thereto, a scoop-bucket supported by the carriage and swivel-mounted for movement from a central loading position into two extremes of oppositely directed rolling travel, manually released means for locking the bucket in its loading position, a source of power, and an elevator chain leading from the power source and having operative interconnection with the bucket and the carriage, the connection with the bucket being a direct connection serving to impart an upward roll-tilting the bucket about its swivel axis as a center and the connection with the carriage being a lost-motion connection serving to impart elevational movement to the carriage only upon the completion of said rolling tilt.

11. In combination with a carriage, and a framework guidably supporting said carriage for vertical movement and upon its head end carrying a sheave, a swivel-mounted scoop-bucket supported by said carriage and providing an integral digging blade adapted when loaded to occupy a level position and arranged by the bucket's swivel movement to be tilted upwardly or downwardly into either a load-carrying or a load-dumping position, respectively, a retractable pawl having a localized mounting in relation to the carriage, a roller also having a localized mounting in relation to the carriage, said bucket being provided with a keeper arranged to engage said pawl and releasably lock the bucket when the bucket occupies its loading position and also presenting a stop-lug engaged by the pawl when the bucket is swung upwardly into load-carrying position, a motor, and a draw-line leading from the motor over said sheave and running downwardly therefrom to pass under the roller and thence horizontally over the bucket into operating engagement with the latter, the bucket, upon a release of said lock, being first rolled by the draw-line from the loading into the load-carrying position and then, as the rolling movement is interrupted by the stop-lug, being elevated bodily with the carriage.

12. In combination with a carriage, and a framework guidably supporting the carriage for vertical movement, a harness pivotally hung from the carriage and at its lower end bearing against the carriage for resistance to horizontal thrust, a scoop-bucket trunnion-mounted in the harness for swivel movement from a neutral loading position into two extremes of oppositely directed rolling travel and formed with a curved back-wall the perimeter of which lies concentric to the swivel axis, a keeper and a stop-lug disposed in aligned spaced relation within a circumference of said back-wall, a retractable pawl carried by the harness to occupy an interruptive position in the path of movement of the keeper and the pawl and acting, when the bucket occupies its loading position, to engage the keeper for releasably locking the bucket and, when the bucket is rolled upwardly, to engage the stop-lug, a bucket-operating motor, and a draw-chain leading from the motor and extending downwardly to the roller to pass under the same and thence forwardly over the bucket into operating engagement with the latter, the bucket, upon a release of the lock, being first rolled by the draw-line and then, by an interruption of the rolling travel, elevated bodily with the harness and the carriage.

13. In a load-handling machine and in combination with a carriage, and a framework guidably supporting the carriage for vertical movement, a harness pivotally hung from the carriage and its lower end bearing against the carriage for resistance to horizontal thrust, a scoop-bucket trunnion-mounted in the harness for swivel movement from a neutral loading position into two extremes of oppositely directed rolling travel and formed with a curved back wall the perimeter of which lies concentric to the swivel axis, a roller journaled upon the harness in rearwardly spaced relation from the bucket, a keeper and a stop-lug disposed in aligned spaced relation within a circumference of said bucket's back wall, a retractable pawl carried by the harness to occupy an interruptive position in the path of movement of said keeper and the pawl and acting, when the bucket occupies its

75

loading position, to engage the keeper for releasably locking the bucket and, when the bucket reaches a point short of the upper extreme of its rolling travel, to engage the stop-lug for interrupting the rolling travel, a depressible dog also carried upon the back wall of the bucket, a bucket-operating motor, a draw-chain activated by the motor and running downwardly to and passing under the roller wherefrom the tail end extends forwardly over the bucket, a connector upon said tail end of the chain arranged to be releasably engaged with the dog, an extensible arm carrying said connector and operating when extended to bring the connector into engagement with the dog, spring means for extending said arm, and means operative upon motor-activated movement of the bucket to the upper extreme of its rolling travel for depressing said dog to free said connector.

20 14. The structure of claim 13 in which the carriage serves as a basic mounting applicable to a severalty of selectively used load-handling attachments and wherein said carriage provides a coupler which is inactive in the use of the scoop-bucket but which permits the alternative attachment of the tail end of the draw-chain directly to the carriage when the employed attachment requires a lift force only.

15. A mobile load-handling machine comprising, in combination with a self-energizing vehicle: a telescoping upright framework carried upon the vehicle to occupy a position at the front end thereof, a carriage guidably supported by the movable element of said telescoping framework for vertical movement in relation thereto, a harness pivotally hung from the carriage with its lower end bearing for horizontal thrust against the latter and presenting forwardly directed cheek-arms, a scoop-bucket trunnion-mounted in the cheek-arms for swivel movement between the two extremes of oppositely directed rolling travel and formed with a curved back wall the perimeter of which lies concentric to the swivel axis, a roller carried by the harness

40 to lie in rearwardly spaced relation from the bucket, a pivoted lever also carried by the harness and providing a pawl, a spring acting upon said lever to normally urge the pawl into bearing engagement against the back wall of the bucket, a manually-operated trip-rope connected with the lever for retracting the pawl, a depressible dog carried upon the back wall of the bucket, a double-keeper and a stop-lug also carried upon the back wall of the bucket and placed the former to engage the pawl and releasably lock the bucket when the bucket occupies a position more or less central to its two extremes of rolling travel and the latter to engage the pawl and interrupt the rolling movement of the bucket at

50 a point short of the upper extreme of its travel, a hydraulic motor, a draw-chain activated by the motor and running downwardly to and passing under the roller with its tail end extending forwardly over the bucket, a connector upon said tail end of the chain arranged to be releasably engaged with the dog, an extensible arm carrying said connector and operating when extended and upon a positioning of the bucket in its said central location to bring the connector into engagement with the dog, a spring acting to extend said arm, and means operative upon motor-activated movement of the bucket to the upper extreme of its rolling travel for depressing said dog to free said connector.

60 16. In combination with a harness, and with a

70

a scoop-bucket trunnion-mounted in the harness for reciprocal rolling movement about the center of the trunnions as an axis, the mechanism for rolling the bucket and which comprises a retractable pawl supported by the harness, a dog carried upon the perimeter of the bucket, a keeper also carried upon the perimeter of the bucket and acting to engage the pawl and releasably lock the bucket when the bucket occupies one position of its rolling travel, a motor, a draw-link powered from the motor and placed more or less tangent to the bucket and upon its tail end carrying a connector arranged to be releasably engaged with the dog, an extensible arm carrying said connector and by its extension acting to bring the connector into engagement with the dog upon a location of the bucket in its said keeper-locked position, and yielding means acting to extend the arm but arranged to be overpowered by the force of the motor.

17. In combination with a harness, and with a scoop-bucket trunnion-mounted in the harness for reciprocal rolling movement about the center of the trunnions as an axis, the mechanism for rolling the bucket and which comprises a retractable pawl supported by the harness, a depressible dog carried upon the perimeter of the bucket, a keeper and a stop-lug also carried upon the perimeter of the bucket and placed the former to engage the pawl and releasably lock the bucket when the bucket occupies one position of its rolling travel and the latter to engage the pawl and interrupt the rolling movement of the bucket at another point in its rolling travel, a motor, a draw-link powered from the motor and having its tail end placed more or less tangent to the bucket, a connector carried upon the tail extremity of said link and arranged to be releasably engaged with the dog, an extensible arm carrying said connector and by its extension acting to bring the connector into engagement with the dog upon a location of the bucket in its said keeper-locked position, yielding means acting to extend the arm but arranged to be overpowered by the force of the motor, and means operative upon a travel of the bucket beyond the interrupted point at which the pawl engages the stop-lug for depressing said dog to free the connector.

18. Structure according to claim 3 in which the carriage admits of having either the scoop-

bucket or a fork-lift supported thereby, and wherein the carriage has a fitting thereon inactive to the powered means when the scoop-bucket is used and which allows the powered means to be coupled directly to the carriage when the fork-lift is used.

19. A mobile scoop comprising, in combination with a mobile mounting, a carriage mounted for vertical movement thereon, a transverse horizontal pivot shaft supported by the carriage to occupy a position adjacent the top end of the latter, a harness hung from said pivot shaft, and a scoop-bucket swivel-mounted in said harness with its swivel axis located below and in outwardly spaced relation from said pivot shaft, the carriage and the harness being so formed as to cause the pendant portion of the harness, when subjected to an end thrust in course of pushing the scoop-bucket into material which is to be loaded, to take a bearing seat against the lower end of the carriage.

20. A mobile scoop comprising, in combination with a mobile mounting, an upright standard supported by the mounting, a carriage guided for vertical movement by the standard, a horizontal pivot-shaft supported by said carriage to occupy a position adjacent the top end of the latter, a harness hung from said pivot-shaft, a scoop-bucket swivel-mounted in said harness with its swivel-axis located below and in outwardly spaced relation from said pivot-shaft, and power means for rolling the scoop-bucket about its swivel axis.

LLOYD THURMAN GRAVES.
